HYDROCARBON CONVERSION

Charles L. Thomas, Chicago, Ill., assignor to Universal Oil Products Company, Chicago, Ill., a corporation of Delaware

Application September 13, 1940, Serial No. 356,596

6 Claims. (Cl. 196—52)

This is a continuation-in-part of my co-pending applications, Serial Numbers 291,889 and 291,890, filed August 25, 1939.

This invention relates to a process for the conversion of hydrocarbon oil into substantial yields of gasoline and more specifically to an improved process combining catalytic with thermal cracking wherein charging oil and selected insufficiently converted hydrocarbons from both thermal and catalytic cracking are subjected to catalytic cracking and the residual portion of the insufficiently converted hydrocarbons from both thermal and catalytic cracking are subjected to thermal cracking.

Catalytic cracking as ordinarily conducted does not employ recycling of insufficiently converted products to the conversion zone because, as has been found, such insufficiently converted hydrocarbons contain a certain amount of undesirable material, the tendency of which is to deposit great amounts of carbon or carbonaceous substances upon the catalyst particles if recycled to the catalyst zone resulting in a more rapid lowering of catalyst activity than is encountered when passing clean unconverted oils in contact with such catalysts. In order to reduce the formation of carbonaceous substances during conversion, resulting in shorter reactivation times and lower peak reactivating temperatures, it is usual to pass the hydrocarbon oil in contact with the catalyst only once and then thermally crack the insufficiently converted oils in a thermal cracking system. In a process employing both thermal and catalytic cracking in the manner above mentioned, the yield and octane of the gasoline product is good but is not as good as one might expect from a process wherein the catalytic recycle is also catalytically cracked.

In my invention involving both catalytic and thermal treatments the two steps have been combined in a novel and advantageous manner so that all of the charging oil comprising, for example, light gas oil, heavy gas oil, naphtha, or kerosene, or, when desired, any mixture thereof, together with light insufficiently converted hydrocarbons separated from the thermally formed reaction products and a portion of the light insufficiently converted hydrocarbons separated from the catalytically formed reaction products is subjected to catalytic cracking while the residual portion of the insufficiently converted hydrocarbons from both steps, including the heavy material from the thermally formed reaction products and a portion of the light material from the catalytically formed conversion products, is subjected

to thermal treatment. Preferably also, the conditions of temperature and pressure employed in the thermal treatment are selected to favor the removal of carbon forming constituents present in the insufficiently converted hydrocarbons from catalytic cracking and to produce lighter hydrocarbons other than gasoline from the heavy insufficiently converted hydrocarbons rather than cracking to gasoline, although some of the latter may occur. By this method, compounds undesirable in catalytic cracking, because of their tendency to form carbonaceous substances which are present in relatively large amounts in the insufficiently converted hydrocarbons, undergo some treatment which converts them into higher boiling hydrocarbons whereby they may be removed as liquid residue in the vaporizing and separating step of the thermal treating system.

In one specific embodiment the invention comprises passing hydrocarbon vapors, including vaporized charging oil and vaporized insufficiently converted hydrocarbons formed in the manner to be described, in contact with a mass of cracking catalyst, fractionating the conversion products to separate fractionated vapors, light reflux condensate and heavy reflux condensate, returning a portion of said light reflux condensate to the catalytic conversion step, commingling the residual portion of said light reflux condensate with said heavy reflux condensate and subjecting the mixture to thermal treatment, commingling the reaction products from said thermal treatment with reaction products formed in a separate thermal treatment as hereinafter set forth and passing the mixture through an elongated reaction chamber wherein substantial further reaction occurs, separating the resulting thermal reaction products into non-vaporous liquid residue and vaporous reaction products, fractionating said vaporous reaction products to separate fractionated vapors, light insufficiently converted hydrocarbons, and heavy insufficiently converted hydrocarbons, returning said light insufficiently converted hydrocarbons to the catalytic conversion step, subjecting said heavy insufficiently converted hydrocarbons to thermal treatment and commingling the reaction products from the last mentioned thermal treatment with those formed in the first mentioned thermal treatment as hereinbefore set forth.

In another embodiment of the invention the heavy reflux condensate from catalytic cracking and the residual portion of the light reflux condensate not returned to the catalytic conversion treatment may be commingled with the heavy in-

sufficiently converted hydrocarbons from the thermal cracking step and the combined mixture subjected to thermal treatment under conditions selected to favor both thermal cracking of the heavy material into lighter hydrocarbons and the desired thermal treatment of the insufficiently converted hydrocarbons from catalytic cracking to remove to a large extent carbon forming substances.

The invention specifically contemplates subjecting all of the charging oil to catalytic cracking, because it has been found that although the charging oil may and usually does contain hydrocarbons boiling above those present in the insufficiently converted hydrocarbons subjected to catalytic cracking, carbon formation is usually not as heavy as would be obtained if the insufficiently converted hydrocarbons from catalytic cracking or the heavy insufficiently converted hydrocarbons from thermal cracking are returned to the catalytic cracking step. Decreased carbon formation is exceedingly advantageous in shortening the time required for reactivating the catalytic material and as a means for decreasing peak reactivating temperatures and consequently the amount of heat generated during reactivation.

The various cooperative features of the present invention may be further understood from a description of a process flow and for this purpose the attached drawing has been provided which shows by the aid of diagrammatic figures in general side elevation an arrangement of interconnected units in which the process may be conducted.

Referring to the drawing, charging oil comprising, for example, naphtha, kerosene, light and heavy gas oils or, when desired, any mixture thereof is supplied through line 1 containing valve 2 to pump 3. Pump 3 discharges through line 4 containing valve 5 after which the oil is commingled with light insufficiently converted hydrocarbons separated in the manner to be described and the mixture introduced to heating coil 6 which receives heat from furnace 7. When desired, steam and/or light gaseous hydrocarbons, the latter comprising either those formed in the process or light gases introduced from an exterior source are commingled with the mixture of hydrocarbon oil in line 4 to aid in substantially completely vaporizing the hydrocarbon oil supplied to heating coil 6 and also as a means for reducing the total pressure on the hydrocarbon oil. In any event, the mixture supplied to heating coil 6 is substantially completely vaporized therein and heated to a temperature ranging, for example, from 800 to 1200° F. preferably while being maintained under a pressure ranging, for example, from substantially atmospheric to 200 pounds or more per square inch.

The heated reactants leaving coil 6 are directed through line 8 containing valve 9 into reactor 10 which contains catalytic material capable of effecting the desired conversion reaction. In the case here illustrated, reactor 10 may comprise, for example, a zone of the heat exchanger type wherein the catalyst is contained in a plurality of elongated tubular elements of relatively small diameter and wherein provisions are made for passing some suitable heat convective medium such as combustion gases in contact with the exterior of said elongated tubular elements whereby to supply heat to the reactants during conversion and to effect cooling during reactivation of the mass of catalytic material. Reactor 10, on

the other hand, may comprise a cylindrical vessel which is well insulated to reduce radiation losses and which contains one or a plurality of beds of catalytic material wherein the reaction may be accomplished substantially adiabatically.

In the catalytic cracking of hydrocarbons relatively large amounts of carbonaceous substances are formed which deposit upon the catalytic material thereby reducing its active surface and necessitating reactivation at periodic frequent intervals. The invention contemplates reactivating the used catalytic material in the usual manner, such as, for example, by passing oxygen-containing reactivating gases in contact with the used catalytic material and removing carbonaceous substances as combustion gases along with the spent reactivating gases. It is desirable, therefore, in order that the operation may be carried out as a continuous process to employ at least two reactors and in some instances more than two reactors so that while the catalytic material in one reactor is being used for effecting conversion of the hydrocarbon reactants the catalytic material in the other or others may be undergoing reactivation.

Catalysts which have been found to be effective in the catalytic cracking of hydrocarbon vapors may comprise pellets or granules of silica or other siliceous and refractory materials composited with compounds selected from the group consisting of alumina, zirconia, and thoria. In addition, the hydrosilicates of alumina, acid treated clays, or the like, have also been found to be effective in the cracking treatment of hydrocarbon vapors. Although the catalysts above recited are generally considered to be preferred catalysts their use is not to be construed as a limiting feature, for various other catalysts well known to those in the art may be employed within the broad scope of the invention.

The conversion products leaving reactor 10 are directed through line 11 containing valve 12 into fractionator 13 which, together with the condensing and collecting equipment in communication therewith, may be operated under a super-atmospheric pressure ranging, for example, from substantially atmospheric to 200 pounds or more per square inch. The conversion products supplied to fractionator 13 are fractionated therein to separate fractionated vapors boiling substantially in the range of gasoline from the higher boiling insufficiently converted hydrocarbons, the latter being condensed in the fractionator and further separated therein into light insufficiently converted hydrocarbons and heavy insufficiently converted hydrocarbons, the light insufficiently converted hydrocarbons preferably comprising those boiling below 650° F. while the heavy insufficiently converted hydrocarbons include all the insufficiently converted hydrocarbons boiling above said light insufficiently converted hydrocarbons.

Fractionated vapors separated in fractionator 13 are directed through line 14 containing valve 15 to cooling and condensation in condenser 16. Distillate, together with undissolved and uncondensed gases in condenser 16, is directed through line 17 containing valve 18 into receiver 19 wherein the distillate and undissolved and uncondensed gases are collected and separated. Undissolved and uncondensed gases separated in receiver 19 are removed by way of line 20 containing valve 21 and may be recovered as a product of the process or as above mentioned a portion thereof may be commingled with the charging oil for

use in the manner previously described. A portion of the distillate collected and separated in receiver 19 may be returned to the upper portion of fractionator 13 by well known means, not shown, as refluxing and cooling medium while the residual portion thereof is removed from receiver 19 by way of line 22 containing valve 23 and recovered as a product of the process or subjected to any desired further treatment.

Light insufficiently converted hydrocarbons separated in fractionator 13 are directed through line 24 containing valve 25 to pump 26. Pump 26 discharges through line 27 and all of the light insufficiently converted hydrocarbons may be directed through line 28 containing valve 29 into line 34 where they commingle with the heavy insufficiently converted hydrocarbons removed from fractionator 13 in the manner to be described. Preferably, however, at least a portion of the light insufficiently converted hydrocarbons in line 27 is directed through valve 30, commingling with the charging oil in line 4 for treatment in the manner previously described. In some instances, the volume of light insufficiently converted hydrocarbons, separated in fractionator 13, returned to the catalytic cracking step, may be substantially equal to the volume of charging oil with no undue amount of carbon deposition. However, it is usually desirable to return less of light insufficiently converted hydrocarbons than the volume above mentioned to catalytic cracking and subject the greater portion thereof to thermal treatment in the manner to be described.

The heavy insufficiently converted hydrocarbons separated in fractionator 13 are directed through line 31 containing valve 32 to pump 33. Pump 33 discharges through line 34 containing valve 35 and the heavy insufficiently converted hydrocarbons are commingled with the light insufficiently converted hydrocarbons diverted through line 28 and valve 29 in the manner previously described, the mixture being directed through valve 36 into heating coil 37 which receives heat from furnace 38. In some cases, however, instead of using a separate heating coil for treating the insufficiently converted hydrocarbons from fractionator 13, the mixture in line 34 may be directed through line 39 containing valve 40 into line 70, after which it may be subjected to treatment in commingled state with heavy reflux condensate separated in the manner to be described.

When heating coil 37 is employed, the insufficiently converted hydrocarbons in passing therethrough are subjected to temperature and pressure conditions selected to favor reactions which tend to convert the undesirable carbon forming constituents contained therein into heavier hydrocarbons which are removed from the process as liquid residue in the manner to be described. Temperatures to which the insufficiently converted hydrocarbons may be heated in coil 37 will fall within the range of 800 to 1000° F. while employing a superatmospheric pressure ranging, for example, from 100 to 1000 pounds or more per square inch.

The heated products leaving coil 37 are directed through line 41 containing valve 42 into line 45 where they commingle with the conversion products formed in the manner to be described. Heavy reflux condensate separated in the manner to be described is introduced to heating coil 43 which receives heat from furnace 44. When desired, as above mentioned, the heavy reflux condensate may be commingled with the insuffi-

ciently converted hydrocarbons separated in fractionator 13 and the mixture subjected to treatment in coil 43. In any event, the hydrocarbons introduced to coil 43 are heated therein to a temperature ranging, for example, from 800 to 1100° F. or thereabouts, while employing a superatmospheric pressure ranging, for example, from 100 to 1000 pounds or more per square inch. The heated products leaving coil 43 by way of line 45 are directed through valve 46 and when heating coil 37 is employed are commingled with the heated products from that coil in the manner previously described. The reaction products in line 45 are then introduced to reaction chamber 47 wherein the conversion reaction instigated in the heating coil proceeds to a proper degree of completion. Reaction chamber 47, in the case here illustrated, is preferably operated under a superatmospheric pressure substantially the same or slightly less than that employed in the communicating heating coil and preferably also is insulated to reduce radiation losses therefrom, although no insulation appears in the drawing.

Reaction products leaving reaction chamber 47 are directed through line 48 containing valve 49 into vaporizer and separator 50. When desired, the use of reaction chamber 47 may be obviated by providing sufficient soaking time in the communicating heating coils to allow the reaction to proceed to the proper degree of completion and introducing the reaction products from these heating coils directly to vaporizing and separating chamber 50 and since the means for accomplishing this are well known, such means are not illustrated.

Vaporizing and separating chamber 50 is preferably operated at a reduced pressure relative to that employed in the reaction chamber and/or the heating coils which may range, for example, from substantially atmospheric to 200 pounds or more per square inch. Vaporous reaction products are separated from the non-vaporous liquid reaction products in chamber 50 and the latter substantially further vaporized to form a non-vaporous liquid residue which is removed from chamber 50 by way of line 51 containing valve 52, recovered as a product of the process or subjected to any desired further treatment.

Vaporous reaction products, including vapors evolved within chamber 50, are directed through line 53 containing valve 54 into fractionator 55. Fractionator 55, together with condensing and collecting equipment in communication therewith, is preferably operated at a pressure substantially equal to that employed in chamber 50. Vaporous reaction products supplied to fractionator 55 are fractionated therein to separate fractionated vapors boiling substantially in the range of gasoline from the higher boiling reaction products and the latter condensed as light and heavy reflux condensate. Light reflux condensate separated in fractionator 55 preferably include those hydrocarbons boiling below 650° F. while the heavy reflux condensate includes all hydrocarbons boiling above the light reflux condensate.

Fractionated vapors separated in fractionator 55 are conducted through line 56 containing valve 57 to cooling and condensation in condenser 58. Distillate, together with undissolved and uncondensed gases from condenser 58, is directed through line 59 containing valve 60 into receiver 61 wherein the distillate and gases are collected and separated. Undissolved and uncondensed gases collected and separated in receiver 61 are

removed therefrom by way of line 62 containing valve 63, recovered as a product of the process or subjected to any desired further treatment. A portion of the distillate collected and separated in receiver 61 is returned to the upper portion of fractionator 55 by well known means, not shown, as a refluxing and cooling medium while the residual portion thereof is removed from receiver 61 by way of line 64 containing valve 65, recovered as a product of the process, subjected to stabilization or to any desired further treatment.

Heavy reflux condensate separated in fractionator 55 is directed through line 66 containing valve 67 to pump 68. Pump 68 discharges through valve 69 and line 70 into heating coil 43 and, as above mentioned, prior to the introduction of the heavy reflux condensate to heating coil 43, it may be commingled with the insufficiently converted hydrocarbons from fractionator 43. Light reflux condensate separated in fractionator 55 is directed through line 71 containing valve 72 to pump 73 which discharges through line 74 containing valve 75 into line 4 where said light reflux condensate commingles with the charging oil for treatment in the manner previously described.

An example of one specific operation of the process as it may be accomplished in an apparatus such as illustrated and above described is approximately as follows: Charging oil comprising a 33° A. P. I. gravity Mid-Continent gas oil is commingled with light insufficiently converted hydrocarbons separated in the manner to be described. The mixture is vaporized and heated to a temperature of 950° F. and the heated vapors passed in contact with a mass of synthetically prepared silica-alumina-zirconia catalyst at a pressure of 30 pounds per square inch. The catalytic conversion products are fractionated to separate fractionated vapors of 400° F. end point from the higher boiling insufficiently converted hydrocarbons. The fractionated vapors are subjected to cooling and condensation and the resulting distillate and gas collected and separated.

The insufficiently converted hydrocarbons separated as above mentioned are condensed in the fractionator and separated into light insufficiently converted hydrocarbons and heavy insufficiently converted hydrocarbons. A portion of the light insufficiently converted hydrocarbons approximately equal in volume to the charging oil is supplied to the catalytic conversion step while the residual portion thereof is commingled with the heavy insufficiently converted hydrocarbons and the mixture subjected to non-catalytic thermal treatment at a temperature of 850° F. and a superatmospheric pressure of 300 pounds per square inch. The reaction products leaving the last step are commingled with other reaction products formed in a separate non-catalytic thermal treatment in the manner to be described and the mixture supplied to a vaporizing and separating chamber operated at a superatmospheric pressure of approximately 25 pounds per square inch. Non-vaporous liquid residue is separated from the vaporous reaction products in the vaporizing and separating chamber and the liquid residue recovered as a product of the process.

The vaporous reaction products separated as above mentioned are fractionated to separate fractionated vapors of approximately 400° F. end point from the higher boiling reaction products. The fractionated vapors are subjected to cooling and condensation and the resulting distillate and gas collected and separated. The higher boiling reaction products are condensed in the frac-

tionator as light and heavy reflux condensate and the light reflux condensate supplied to the catalytic conversion step. The heavy reflux condensate is subjected to thermal treatment separate from the first mentioned thermal treatment at a temperature of 920° F. and at a superatmospheric pressure of 300 pounds per square inch and the reaction products resulting therefrom commingled with the first mentioned reaction products in the manner previously described.

From an operation employing conditions as above mentioned one may obtain approximately 45.2% of 400° F. catalytically cracked gasoline having an octane rating of 80, approximately 22.9% of 400° F. thermally cracked gasoline of 69 octane rating, 20.0% of liquid residue of 8° A. P. I. gravity, the balance being principally carbon, gas, and loss.

I claim as my invention:

1. A process for the conversion of hydrocarbon oil which comprises passing vapors of said hydrocarbon oil at a cracking temperature in contact with a mass of cracking catalyst, fractionating the conversion products to separate fractionated vapors, light insufficiently converted hydrocarbons, and heavy insufficiently converted hydrocarbons, supplying a portion of said light insufficiently converted hydrocarbons to the catalytic conversion step, commingling the residual portion of said light insufficiently converted hydrocarbons with said heavy insufficiently converted hydrocarbons and subjecting the mixture to non-catalytic thermal treatment, separately fractionating vaporous reaction products from said non-catalytic thermal treatment to separate fractionated vapors, light reflux condensate, and heavy reflux condensate, supplying said light reflux condensate to the catalytic conversion step and said heavy reflux condensate to the non-catalytic thermal treatment, and finally condensing the fractionated vapors.

2. A process for the conversion of hydrocarbon oil which comprises passing vapors of said hydrocarbon oil at a cracking temperature in contact with a mass of cracking catalyst, fractionating the conversion products to separate fractionated vapors, light insufficiently converted hydrocarbons, and heavy insufficiently converted hydrocarbons, supplying a portion of said light insufficiently converted hydrocarbons to the catalytic conversion step, commingling the residual portion of said light insufficiently converted hydrocarbons with said heavy insufficiently converted hydrocarbons and subjecting the mixture to non-catalytic thermal treatment, separately fractionating vaporous reaction products from said non-catalytic thermal treatment to separate fractionated vapors, light reflux condensate, and heavy reflux condensate, supplying said light reflux condensate to the catalytic conversion step, subjecting said heavy reflux condensate to a non-catalytic thermal treatment separate from the first mentioned thermal treatment and fractionating the vaporous reaction products from the last mentioned thermal treatment in commingled state with the vaporous reaction products from the first mentioned thermal treatment, and finally condensing the fractionated vapors.

3. A process for the conversion of hydrocarbon oil which comprises passing vapors of said hydrocarbon oil at a cracking temperature in contact with a mass of cracking catalyst, fractionating the conversion products to separate fractionated vapors, light insufficiently converted hydrocarbons having an end boiling point not

substantially in excess of 650° F. and heavy insufficiently converted hydrocarbons containing the fractions of said conversion products boiling above 650° F., supplying a portion of said light insufficiently converted hydrocarbons to the catalytic conversion step, commingling the residual portion of said light insufficiently converted hydrocarbons with said heavy insufficiently converted hydrocarbons and subjecting the mixture to non-catalytic thermal treatment, separately fractionating vaporous reaction products from said non-catalytic thermal treatment to separate fractionated vapors, light reflux condensate having an end boiling point not substantially in excess of 650° F. and heavy reflux condensate containing the fractions of said vaporous reaction products boiling above 650° F., supplying said light reflux condensate to the catalytic conversion step, subjecting said heavy reflux condensate to a non-catalytic thermal treatment separate from the first mentioned thermal treatment and fractionating the vaporous reaction products from the last mentioned thermal treatment in commingled state with the vaporous reaction products from the first mentioned thermal treatment, and finally condensing the fractionated vapors.

4. A process for the conversion of hydrocarbon oil which comprises passing vapors of said hydrocarbon oil at a cracking temperature in contact with a mass of cracking catalyst, fractionating the conversion products to separate fractionated vapors, light insufficiently converted hydrocarbons, and heavy insufficiently converted hydrocarbons, supplying a portion of said light insufficiently converted hydrocarbons to the catalytic conversion step, commingling the residual portion of said light insufficiently converted hydrocarbons with said heavy insufficiently converted hydrocarbons and subjecting the mixture to non-catalytic thermal treatment in a heating coil and 40 communicating reaction chamber, separating non-vaporous liquid residue from the non-cata-

lytic thermally formed vaporous reaction products, separately fractionating said vaporous reaction products to separate fractionated vapors, light reflux condensate, and heavy reflux condensate, supplying said light reflux condensate to the catalytic conversion step and said heavy reflux condensate to the non-catalytic thermal treatment, and finally condensing the fractionated vapors.

5. The process defined in claim 4 further characterized in that the heavy reflux condensate is subjected to thermal treatment in a separate heating coil and the reaction products thereafter commingled with the reaction products formed 15 in the thermal treatment of the insufficiently converted hydrocarbons from the catalytic cracking step prior to their introduction to the reaction chamber.

6. A process for the conversion of hydrocarbon oil which comprises passing vapors of said hydrocarbon oil at a cracking temperature in contact with a mass of synthetically prepared silica-alumina-zirconia catalyst, fractionating the conversion products to separate fractionated vapors, light insufficiently converted hydrocarbons, and heavy insufficiently converted hydrocarbons, supplying a portion of said light insufficiently converted hydrocarbons to the catalytic conversion step, commingling the residual portion of said light insufficiently converted hydrocarbons with said heavy insufficiently converted hydrocarbons and subjecting the mixture to non-catalytic thermal treatment, fractionating vaporous reaction products from said non-catalytic thermal treatment to separate fractionated vapors, light reflux condensate, and heavy reflux condensate, supplying said light reflux condensate to the catalytic conversion step and said heavy reflux condensate to the non-catalytic thermal treatment, and finally condensing the fractionated vapors.

CHARLES L. THOMAS.
